UNITED STATES PATENT OFFICE

162,520

GARMENT HANGER

Roland W. Colwell, Los Angeles, Calif.; Joseph W. Colwell, executor of said Roland W. Colwell, deceased

Application August 19, 1949, Serial No. 4,614

Term of patent 14 years

(Cl. D80—8)

To all whom it may concern:

Be it known that I, Roland W. Colwell, a citizen of the United States, residing at Los Angeles, in the county of Los Angeles, and State of California, have invented a new, original, and ornamental Design for a Garment Hanger, of which the following is a specification, reference being had to the accompanying drawing, forming a part thereof.

Fig. 1 is a perspective view of a garment hanger showing my new design.

Fig. 2 is a rear elevation of the hanger shown in Fig. 1.

I claim:

The ornamental design for a garment hanger, substantially as shown.

ROLAND W. COLWELL.
